UNITED STATES PATENT OFFICE

GEORGE F. THAXTON, OF SAVANNAH, GEORGIA

LOCKED LAUNDRY BAG

Application filed April 6, 1928. Serial No. 268,004.

Primarily my present invention has reference to a method and means whereby a housewife sending clothes to a laundry is assured that no mistake will be made and 5 that the original package will be returned her.

Specifically the improvement resides in the employment of mesh bags for the reception of clothes to be laundered, simple but 10 novel means for sealing the bag and said means including a lock or seal bearing a serial number or like indicating character, and the key for unlocking the sealing means bearing a similar serial number or character and 15 being retained in possession of the housewife while the clothes are laundered so that the bag, when returned from the laundry can be opened only by the holder of the key or like 20 unlocking means; the clothes being laundered while in the bag.

The improvement is illustrated by the accompanying drawings and will be clearly described in the following specification and specifically set forth in the claim.

25 In the drawings:

Figure 1 is an elevation of my improvement.

Figure 2 is an end view thereof.

Figure 3 is a sectional view on the line 30 3—3 of Figure 1.

Figure 4 is a view of the key with the tag attached thereto.

Figure 5 is a perspective view of the slide.

Figure 6 is a similar view of the clamp.

35 My invention is designed to include mesh bags 1. The open mesh bags are preferably formed of heavy netting or other material that will insure the strength thereof, so that the same will withstand the strain to which it 40 is subjected when placed in the laundering machine and when acted on by the centrifugal water extractors.

45 Before entering a detailed description of my improved method I will set forth the means for sealing the mouth of the bags 1. This means, as clearly disclosed by the drawings includes a clamping member 2. The clamping member is formed from a single strip of spring metal that is rust-proof and 50 that is centrally rounded upon itself to pro-

vide inwardly arched arms or sides 3, and the free ends of these sides 3 are in contacting engagement. The arms or sides 3 of the clamp are spread when the same is arranged over the mouth or neck of the bag and the bag 55 1, is, of course, compressed between the arms of the clamp as clearly disclosed by Figure 3 of the drawings. As stated, the free ends of the arms of the clamp exert a pressure toward each other, and this permits of the 60 arrangement of the said ends over a slide 4. The slide is in the nature of a metal plate of non-corrosive material, the said plate being formed with a central opening 5 that receives therethrough the ends of the clamp 65 2. The slide is brought against the folded neck of the bag to cause the same to be properly bunched against the inner surface of the clamp. The arms 3 of the clamp 2, at a distance inward from their contacting ends have 70 alining openings therethrough, and there is adapted to be passed through these openings the shackle 7 of a lock 8.

75 The slide 4, and the clamp 2 may, if desired, bear similar serial numbers or like indicia but as any of the slides 4 may be arranged over any of the clamps 2 this might cause a confusion. Therefore each of the locks 8 is provided on its outer face with a serial number or like indicating indicia 10 and the key 80 11 for each of the locks 8 has attached thereto by a ring or similar means 12 a tag 13 that bears a serial number or indicia 14 corresponding to the serial number or indicia 10 on the lock 8. 85

The system may be briefly described as follows: The laundry driver calls at the customer's house for a washing equipped with two or more of the nets having the locks and keys bearing the same serial number or like 90 indicia. The customer has the washing already assorted into white and colored bundles, or in case of light flimsy white clothes she may have a bundle of light white and a bundle of heavy white which would be placed 95 in different net bags. In any case he would place the clothes in the several bags and they will be locked or sealed by the driver in her presence and the numbered key will be left in her possession. The driver makes 100

note of the serial number on the locks of the bags received, so that they will be returned after the clothes therein are laundered to the proper customer. The net bags containing the clothes are placed in the laundry machine and after being washed and the water thereof forced therefrom by the usual centrifugal extractors, the driver again returns the bag, with the laundered clothes therein, to the housewife. The housewife produces her numbered key, unlocks the bag and empties her clothes and returns the net, together with the locking or clamping means to the driver and the transaction is thus brought to a finish.

The advantages of my improved method and means is that the housewife can get her clothes wet washed without anyone else handling the individual pieces. The nets are sealed or locked from the time they leave the housewife until returned so that there can be no loss or theft of the clothes sent to the laundry. The housewife assorts her own clothes, thereby insuring each of her classifications receiving proper treatment and eliminates error of classification by some laundry employee through carelessness. Thus the improvement tends to increase the confidence in the laundry and should increase the business of the laundry.

Having described the invention, I claim:

The combination with a mesh laundry bag, of means for sealing the mouth thereof, said means comprising a substantially U-shaped clasp formed from spring metal, the free ends of the arms of the clasp being normally engaged and exerting a tension toward each other, said substantially U-shaped clasp being designed to be arranged about the mouth 40 of the bag, a metallic plate having a centrally disposed slot therein for receiving the free ends of the arms, said free ends having openings therein to receive the hasp of a lock to retain the plate on the arms and a key for said lock and said lock and key having corresponding identification indicia thereon.

In testimony whereof I affix my signature.

GEORGE F. THAXTON.
